UNITED STATES PATENT OFFICE.

BERTRAM A. STROOCK, OF NEW YORK, N. Y., ASSIGNOR TO STROOCK PLUSH COMPANY, OF NEWBURGH, NEW YORK, A CORPORATION OF NEW YORK.

DESIGN FOR PLUSH FABRIC.

46,352.

Specification for Design.

Patented Sept. 1, 1914.

Application filed May 7, 1914. Serial No. 837,063. Term of patent 14 years.

To all whom it may concern:

Be it known that I, BERTRAM A. STROOCK, a citizen of the United States, residing at New York city, in the county of New York and State of New York, have invented a new, original, and ornamental Design for Plush Fabric, of which the following is a specification, reference being had to the accompanying drawing, forming part thereof, in which is represented a view of the face or finished side of the fabric.

I claim:

The ornamental design for plush fabric, as shown.

BERTRAM A. STROOCK.

Witnesses:

EDWARD STRICKER,
Jos. M. HAMBLATT.
